UNITED STATES PATENT OFFICE.

FRANK W. MERRICK, OF BOSTON, MASSACHUSETTS, ASSIGNOR TO UNION LOCK STITCH COMPANY, OF BOSTON, MASSACHUSETTS. A CORPORATION OF MAINE.

SEWING-MACHINE.

1,077,625.

Specification of Letters Patent.

Patented Nov. 4, 1913.

Application filed July 8, 1901. Serial No. 67,395.

To all whom it may concern:

Be it known that I, FRANK W. MERRICK, a citizen of the United States, residing at Boston, in the county of Suffolk, State of Massachusetts, have invented a certain new and useful Improvement in Sewing-Machines, of which the following is a specification, reference being had therein to the accompanying drawings.

10 The invention consists in improved feeding arrangements designed more especially for employment in hooked needle wax-thread sewing machines.

A machine embodying the present invention, in the best form thereof which I have yet contrived, is represented in the accompanying drawings, in which latter—

Figure 1 shows the said machine in section in a vertical plane extending lengthwise of the main or driving shaft of the machine. Fig. 1^a is a detail of the feeding mechanism. Fig. 2 shows the said machine partly in end elevation viewed from the left hand side in Fig. 1, and partly in vertical section. Fig. 3 is a detail view of certain portions of the feed mechanism, partly in vertical section. Fig. 4 is a detail view thereof in plan, partly in horizontal section. Fig. 5 is a sectional elevation of the presser-foot lifting mechanism.

The fixed frame or casting of the machine comprises the base *a*, the needle-post *a'* carrying the work-support *a''*, the main post *a''*, and the overhanging arm or gooseneck *a'''*. The head of the machine is designated *b*, the same being formed or provided with suitable bearings in which work the awl-bar *c* carrying the awl *c'*, and the presser-bar *d* carrying the presser-foot *d'*. For the actuation of the awl-bar *c*, the latter is connected operatively in suitable manner with the rotating shaft *e* extending through the upper portion of post *a''* and also lengthwise of arm *a'''*. Herein, the connection comprises a link *c''* which is combined in usual manner with a crank *c'''* fast with the left-hand end of shaft *e*. Shaft *e* is, in the present case, the driving shaft of the machine.

In carrying one portion of my invention into effect, I form the head *b* of the machine with a cylindrical extension or sleeve, as *b'*, and I bore out the arm or gooseneck *a'''* to receive the same, the said extension or sleeve fitting within the bore of the said arm or gooseneck, which is formed or provided

with one or more bearings therefor, as shown clearly in Fig. 1. Extension or sleeve *b'* itself is formed or provided with one or more bearings for the left-hand portion of the shaft *e*, which is passed therethrough. It will be perceived that inasmuch as the cylindrical extension or sleeve *b'* and the bearings therefor in arm or gooseneck *a'''* are concentric with shaft *e*, said cylindrical extension or sleeve and the head *b* may be rocked freely as required in occasioning the lateral or feeding movements of the awl and presser-foot, without interfering with the proper working of the parts or disturbing the relations thereof with respect to one another.

In its most complete form the machine embodying the invention includes a clamping member *f* arranged at the opposite side from the presser-foot *d'* relative to the material to be operated upon. The under clamp *f* is mounted at the upper end of a post *f'* with which a rocker *f''* is provided, and it works in a slot *a''''* with which work support *a''''* is formed. For the purpose of causing the under clamp *f* to move laterally in unison with the awl *c'* and presser-foot *d'* in effecting the feed of the material to be operated upon, rocker *f''* is operated synchronously with the head *b* and in the same direction therewith. The means of operating the head *b* and rocker *f''* in unison may vary more or less in practice. The drawings show attached to the inner portion of the cylindrical extension or sleeve *b'* pertaining to head *b* a depending arm *b''* having a slotted or open lower end, as shown in detail in Fig. 1^a, and the rocker *f''* is furnished with an arm *f''''* extending upwardly therefrom. The upper end of arm *f''''* carries a roll *f'''''* working in the slot or opening *b''* of arm *b''*. Thereby arms *b''* and *f''''* are connected so that head *b* and post *f'* shall swing in unison and in the same direction. With the upper end of arm *f''''* I connect pivotally at *f''''* the lower arm of a lever *g*, see more especially Fig. 3, the said lever having a slotted or forked upper end, in the slot *g'* of which works the cam *y* on shaft *e*. Lever *g* is pivotally connected at *g''*, Figs. 3 and 4, as by center screws, with one extremity of a slotted or open link *g''''*, within the opening of which the lever *g* works, the other extremity of said link being connected at *g''''*, as by center screws, with an open or yoke-

shaped hand-lever g^5 , which, in turn, is pivoted at g^6 , as by center screws, to suitable projections g^7 connected with the post a^3 . By adjustment of hand-lever g^5 the extent of the feed movement is varied.

5 A hooked needle is shown at h , it working upward from below through a slot in the under clamp f , and being carried by the needle-bar h' , which latter is operatively connected by link h^2 with an arm of rocker h^3 located within base a of the machine, the said rocker having a second arm which has connected therewith the lower extremity of a rod h^4 provided with a strap fitting an 10 eccentric at h^5 on shaft e . The usual thread-carrier for laying the thread into the open eye of needle h is represented at i , it being attached to a rocking arm i' which is constructed, arranged, and operatively combined with an eccentric on shaft e , as at i^2 , substantially as in my United States Letters Patent No. 490,856, granted January 31, 1893, to which reference may be had.

15 The swinging arm i^3 on which arm i' is mounted is pivoted at i^4 , Fig. 1, to the brackets a^5 projecting from arm a^4 .

In the form of machine in which the various features of the invention are shown embodied, the usual cast-off is dispensed 20 with, the needle being adapted to shed or discharge the loop without the aid of a cast-off for the purpose. The essential operations of sewing are performed by the awl, needle, and thread-guide. The machine is 25 greatly simplified through the employment of a self-discharging needle and the omission of the cast-off and its associated parts, and a much higher rate of speed is attained in practice than could be secured if these 30 were employed.

The spring for depressing the presser-bar and presser-foot is shown at d^2 , see more especially Fig. 5, it being in the present case in the form of a spiral spring that is compressed between a collar d^3 attached to the upper portion of presser-bar d , and a collar d^4 carried by a screw d^5 fitting a screw-threaded hole in a bracket d^6 attached to head b . By turning the said screw the tension of the spring d^2 may be varied in order to adjust the pressure of the presser-foot against the material beneath the latter. For the purpose of lifting the presser-foot manually whenever required, the usual lifting 45 lever d^7 is provided, its forward extremity being arranged to take under an extension of collar d^3 .

At the time at which the feeding movement takes place, the material being stitched 50 is clamped between the presser-foot and the under clamp f . The use of the under clamp or feed, moving in unison with the upper feed, is especially advantageous in closing seams, i. e. in operating upon work in which 55 it is required to start the stitching upon two

or more loose pieces of material lying superimposed upon each other.

In practice, automatic presser-foot lifting mechanism will be employed for the purpose of raising the presser-foot from the material being operated upon (such material being indicated in dotted lines at x in Fig. 1 of the drawings) after each feed movement of the feeding devices and prior to the reverse or return movement of the said devices.

70 I have shown in the accompanying drawings a form of automatic presser-foot lifting mechanism which constitutes the subject of United States Letters Patent No. 879,565, granted to me February 18, 1908.

Briefly described, the said mechanism comprises a sleeve m , see more particularly Fig. 5, fitted upon the presser-bar d within the opening of the head b and between the bearings b^9 b^9 in the said head, to which the

presser-bar is fitted, the said sleeve being slotted transversely as at m' , and receiving in the slot a block m^2 making contact with the surface of the presser-bar, the sleeve being formed, moreover, with an open or

90 slotted bracket m^3 extending horizontally therefrom and receiving within its opening the toggle arrangement which is employed for the purpose of clamping the sleeve and bar together. The said toggle arrangement

95 comprises an abutment screw m^4 having a rounded or convex inner end and applied to a threaded hole which is provided in the outer portion of the bracket m^3 of sleeve m ,

100 a strut m^5 formed with rounded or convex opposite ends and having one of such ends fitted into a cup or concavity in the back of the block m^2 , and a lever m^6 intervening between the proximate ends of the screw m^4 and strut m^5 , the said lever having round-

105 ed concavities in the opposite faces of its upwardly extending arm fitting the convex inner extremity of the said screw and the correspondingly formed outer extremity of the said strut. The lever m^6 has a hori-

110 zontally extending arm resting on the tappet m^7 which is provided on the small rock-shaft m^8 extending transversely across the face of the head at the left hand end of the machine, the said rock-shaft m^8 being pivot-

115 ed to opposite brackets m^9 m^9 with which the head is provided, and having an arm m^{10} which is connected by means of the link m^{11} with a block m^{12} which is made fast to the awl-bar. By the described means the rock-

120 shaft m^8 is actuated from the awl-bar. In the rise of the latter the tappet m^7 is swung upwardly, thereby operating the toggle to clamp the sleeve to the presser-bar, and as

125 soon as the clamping has been effected the continued upward movement of the tappet m^7 operates to raise the connected sleeve and presser-bar. A spring m^{14} surrounds the

130 presser-bar, between the upper end of the sleeve m and a portion of the head b above

the same. It operates at the times when the sleeve is unclamped from the presser-bar, to depress the sleeve so as to hold the lever m^6 at all times resting against the tappet m^7 or the surface of the portion of the rock-shaft m^8 from which the said tappet projects.

One advantage of mounting the head to swing in the line of the feed concentrically 10 with the shaft e has already been indicated in this specification. The herein-described construction comprising the cylindrical extension or sleeve with which the head is provided, fitted to bearings in the fixed 15 frame of the machine and itself furnished with bearings receiving the said shaft, is especially compact, simple, durable, and free from liability to wear or breakage. The weight that is located above the axis of 20 oscillation of the head acts to counterbalance the weight that is located below such axis. Consequently, the illustrated machine is particularly well adapted to the attainment and maintenance of exceedingly high 25 speed, and at such speed is free from noise and vibration.

A characteristic of the under clamp f shown in the drawings is the fact that it is fixed to the upright arm f' of rocker f^2 and 30 carried entirely thereby. No guides or the like upon the work-support a^2 are required therefor.

I claim as my invention:—

1. In a sewing machine, in combination, 35 an operating shaft, an awl-bar carrying an awl and a needle-bar carrying a needle, means for imparting endwise motion to the said bars from the said operating shaft, a head having one of said bars guided there- 40 in, and means for producing continuous vi- bratory movement of said head concentri- cally with respect to the said shaft and rela- tive to the latter during the operation of the machine for the purposes of the feed.

2. In a sewing machine, in combination, 45 an operating shaft, an awl-bar carrying an awl and a needle-bar carrying a needle, means for operating said bars, a head hav- 50 ing a sleeve concentric with said shaft and also having one of said bars guided therein, and means for producing continuous vi- bratory movement of said head during the operation of the machine for the purposes of the feed.

3. In a sewing machine, in combination, 55 the fixed frame of the machine, an operating shaft, the head journaled concentrically with the said shaft, means to vibrate the said head around the said shaft and thereby 60 occasion the feed-movement thereof, the presser-bar and presser-foot carried by the said head, and automatic presser-foot lifting mechanism operated from the said shaft.

4. In a sewing machine, in combination, 65 a counter-balanced head mounted to swing

or vibrate, feeding devices carried by the said head, and means to communicate continuous vibratory movement to the said head during the operation of the machine for the purposes of the feed.

5. In a sewing machine, in combination, 70 a rotating operating shaft, a movable head, feeding devices carried by the said head, and means to continuously swing or vibrate said head concentrically around said shaft during the operation of the machine for the purposes of the feed.

6. In a sewing machine, in combination, 75 a rotating drive-shaft, a rocker mounted to swing concentrically around said drive-shaft, feeding means carried by said rocker and made operative to feed by the swinging movement thereof, and actuating-devices operatively connected with the said rocker and transmitting feed-movements to the 80 same.

7. In a sewing-machine, in combination, 85 a rotating drive-shaft, a rocker mounted to swing concentrically around said drive-shaft, a presser-bar and presser mounted in said rocker, means operatively connected with said shaft to vibrate the said rocker around the shaft in the line of the feed, and automatic presser-foot lifting mechanism operated from the shaft.

8. In a chain-stitch sewing machine, in combination, an awl, an awl-bar, a non-rotative needle-bar, a self-discharging straight needle carried thereby operating to discharge the loop therefrom independently of a cast-off, thereby dispensing with the latter, a thread-guide for applying thread to the said needle, and means for operating the said parts to perform sewing.

9. In a sewing machine, in combination, 100 a drive-shaft, a counterbalanced head mounted to swing or vibrate concentrically with the said drive-shaft, feeding means carried by the said head, and means operatively connected with the said drive-shaft 105 to communicate continuous vibratory move- ment to the said head during the operation of the machine, for the purposes of the feed.

10. In a sewing machine, in combination, 110 an operating shaft, the sewing-machine head sleeved concentrically with the said shaft and provided with feeding devices, and actuating devices connected with the sleeve of said head and communicating feed- movements to the head by vibrating it 115 around the shaft.

11. In a sewing machine, in combination, 120 an operating shaft, a feed-cam on said shaft, the sewing-machine head journaled concentrically with the shaft and provided with feeding devices, and devices transmitting movement from the cam to the head and vi- 125 brating the head around the shaft to occa- sion the feed.

12. In a sewing machine, in combination, 130

4
the fixed frame of the machine, an operating shaft, a cam, the head of the machine having a cylindrical extension or sleeve fitting bearings in the said frame concentric with said shaft, the said head having in connection therewith means to engage the material being stitched for the purpose of feeding the said material, an arm connected with the said extension or sleeve, and operative connections between the said cam and arm whereby the feed movements of the head are occasioned by swinging it about the axis of the said shaft as a center.

13. In a sewing machine, in combination, the fixed frame of the machine, an operating shaft, the head of the machine having a cylindrical extension or sleeve fitting bearings in the said fixed frame and itself provided with bearings receiving the said shaft, 15 the said head having in connection therewith means to engage the material being stitched for the purpose of feeding the said material, and means to occasion the feed movements of the said head by swinging it 20 about the axis of the said shaft as a center.

14. In a sewing machine, in combination, the fixed frame of the machine, an operating shaft, the head having the cylindrical extension or sleeve fitted to bearings in the 30 said fixed frame concentric with the said shaft, means to swing the said head to occasion the feed movements thereof, the presser-bar and presser-foot carried by said head, and automatic presser-foot lifting 35 mechanism operated from the said shaft.

15. In a sewing machine, in combination, the head, the presser-bar mounted on the said head, the presser-foot, the under clamp, and means to move said head and under 40 clamp transversely in unison to feed the material being operated upon.

16. In a sewing machine, in combination, the head, the presser-bar mounted on the said head, the presser-foot, the under clamp, 45 the rocker having the said clamp rigidly supported thereby and means to move said head and rocker transversely in unison, whereby the presser-foot and under clamps are caused to move in unison in the line of 50 the feed.

17. In a sewing machine, in combination, the fixed frame of the machine, an operating shaft, the head mounted to swing concentrically with the said shaft, the presser- 55 bar mounted on said head, the presser-foot, the under clamp, the rocker with which the said clamp is connected, a cam on said shaft, and a lever *g* operatively connected with said head and rocker and actuated by the 60 said cam.

18. In a sewing machine, in combination,

the fixed frame of the machine, an operating shaft, the head mounted to swing concentrically with the said shaft, the presser-bar mounted on said head, the presser-foot, 65 the under clamp, the rocker with which the said clamp is connected, a cam on said shaft, a lever *g* operatively connected with said head and rocker and actuated by the said cam, the link *g* connected with the said lever, and the hand-lever *g* to which said link is also connected.

19. In a sewing machine, in combination, the fixed frame of the machine, an operating shaft, the head having the cylindrical 75 extension or sleeve fitting bearings in the said frame and itself provided with bearings receiving the said shaft, the presser-bar mounted on said head, the presser-foot, the under clamp, the rocker with which the said 80 clamp is connected, the arms connected with said cylindrical extension or sleeve and rocker, the lever operatively connected with said arms, and the cam on said shaft actuating said lever.

20. In a sewing machine, in combination, the fixed frame of the machine, an operating shaft, the head having the cylindrical extension or sleeve fitting bearings in the said frame and itself provided with bearings receiving the said shaft, the presser-bar mounted on said head, the presser-foot, the under clamp, the rocker with which the said clamp is connected, the arms connected with said cylindrical extension or sleeve and 90 rocker, the lever operatively connected with said arms, the cam on said shaft actuating said lever, the link connected with said lever, and the hand-lever with which said link is 95 also connected.

21. In a sewing machine, in combination, the fixed frame of the machine, an operating shaft, the head having the cylindrical extension or sleeve fitting bearings in the said frame and itself provided with bearings receiving the said shaft, the presser-bar mounted on said head, the presser-foot, the under clamp, the rocker with which the said clamp is connected, the arms connected with said cylindrical extension or sleeve and 105 rocker, the lever operatively connected with said arms, the cam on said shaft actuating said lever, the link connected with said lever, and the hand-lever with which said link is 110 also connected.

115
In testimony whereof I affix my signature, in presence of two witnesses.
